UNITED STATES PATENT OFFICE

HARRY P. SHRIVER, OF VAN WERT, OHIO, ASSIGNOR TO KENNEDY MANUFACTURING COMPANY, OF VAN WERT, OHIO, A CORPORATION OF INDIANA

CARRYING CASE

Application filed February 5, 1930. Serial No. 485,928.

This invention relates to sheet metal carrying cases and particularly to such cases containing trays which may be moved into an outwardly extending position.

One of the objects of the present invention is to provide a water-proof sheet metal kit or carrying case having a pair of covers and containing one or more trays which may be moved into an outwardly extending position by the opening of the covers.

Another object is to provide a sheet metal case containing one or more trays with covers for moving the trays to outwardly extending position, the covers and trays being shaped to provide easy access to the trays and box portion of the case when the covers are opened.

Another object is to provide a sheet metal carrying case containing one or more trays with covers for moving the trays to extended position over the sides of the case, which covers are adapted to overlap each other when closed to provide a substantially waterproof case.

A further object is to provide a sheet metal carrying case containing two series of superposed trays disposed side by side which, when in normal position, are spaced above the bottom of the case to form a storage space.

A still further object is to provide a sheet metal carrying case which is neat and compact and which may be used for a variety of purposes including, for example, the carrying of fishing tackle, make-up for theatrical people, sign painters' equipment, and the carrying of supplies for many other purposes.

With the above and other objects in view which will be apparent from the detailed description to follow, and the appended claims, the present invention consists in certain novel features of construction and combinations of parts which will be readily understood by those skilled in the art to which the invention appertains.

In the drawings which illustrate a suitable embodiment of the present invention,

Figure 1 is a perspective view showing the same in closed position for convenient transportation.

Figure 2 is an end view of the carrying case shown in Fig. 1 showing one of the covers in closed position and the other in partially open position.

Fig. 3 is an end view of the carrying case showing both sets of trays in extended position, a portion of one end of one of the covers being broken away to more clearly show the connecting linkage between the trays and box portion and between the trays and cover portion.

Fig. 4 is a partial longitudinal section of the case taken substantially on the line 4-4 of Fig. 5 when the covers are closed.

Fig. 5 is a section taken substantially on the line 5-5 of Fig. 4 when the covers are closed to show the overlapping relationship between the covers and showing the construction of the sides of the case.

Fig. 6 is an enlarged section taken substantially on the line 6-6 of Fig. 5.

Fig. 7 is an enlarged section showing the double lock seam between the end walls and the bottom and side walls of the box portion.

The present invention contemplates a neat appearing, compact and convenient carrying case having a pair of covers hinged to the sides of the box portion thereof and adapted to overlap each other along the center. The case about to be described in detail is arranged to contain a number of trays which are moved into an outwardly extending position over the side walls of the case by the opening movement of each of the covers. These trays are preferably disposed within the case in two superposed series, the total width of the trays being substantially the same as that of the case in order to provide a maximum carrying capacity. These trays furthermore are disposed well above the bottom of the case when it is closed so that a substantial storage space is provided beneath the trays. The trays and storage space in the carrying case of the present invention are entirely accessible when the covers are opened, whereby articles can be easily disposed therein and removed therefrom.

Referring to the accompanying drawings in which like numerals refer to like parts throughout the several views, the case in gen-

eral comprises a box A, a pair of covers B and C, and trays D, E, F and G disposed within the box A. The box A of the carrying case comprises a bottom 1, side walls 2 and end walls 3. The bottom 1 and side walls 2 are preferably formed from a single continuous sheet of metal as shown in Fig. 5, and are rigidly secured at their edges to the end walls 3 by suitable double-lock seams 4 and 5, respectively. As shown in Fig. 5, the side walls 2 are formed at their upper edges with inwardly offset flanges 6, which flanges are doubled back at their marginal edges 7 to provide smooth edges and to add rigidity to the structure. The integral connections between the offset flanges 6 and the body portions of the walls 2 form shoulders 8 for a purpose to be later described.

The end walls 3, like the side walls 2, are also preferably formed with offset flanges 9 at their upper edges, as shown in Fig. 4, and the marginal edges are bent inwardly to form flanges 10 which support the trays when they are in their normal unextended position.

The trays D, E, F and G are each of substantially rectangular shape and preferably of the same size. These trays are shown as symmetrically disposed with respect to the longitudinal center line of the box A and as approximately one-half the width thereof. The dimensions of the trays, of course, may be varied to suit particular circumstances, and may be divided into compartments of the desired size by suitable partitions (not shown), as is well known in the art. Each series of trays may comprise one or more trays, and for certain purposes one of the series may be omitted so that the trays may be approximately the same width and length as the box A. It is to be noted, however, that the combined width of the two series of trays, when two series are employed, is substantially the same width as the box A.

Each of the trays is preferably formed from a single sheet of metal bent into the required size to form sides 11, a bottom 12 and ends 13 which may be formed with flanged portions 14 that may be welded or otherwise secured to the sides 11. The trays D and F in normal position substantially completely cover the top of the box A and are supported above the bottom 1 of the box by the inwardly extending flanges 10 formed at the uppermost marginal edges of the side wall flanges 9. The trays E and G of the two series, in normal position, seat in superposed relationship upon the trays D and F, respectively.

The covers B and C are each preferably formed from a single piece of sheet metal, and provided with a side 15, an integral top 16 and end walls 17. The connections between the end walls and side and top may, if desired, be strengthened by strips 18 of metal welded or otherwise secured thereto. The inner marginal edges of the top end walls of the

covers B and C are formed with outwardly offset flange portions 19 and 20 extending from the bottom of one end wall up and over the top 16 and down to the lower edge of the other end wall. The portion 19 for the cover B, however, is preferably offset to a greater extent than the portion 20 so that the portions will overlap each other when the covers are closed, as shown in the different views, to provide a substantially water-proof covering for the case.

The lower edge of the cover side walls are provided with suitable hinges 21 which are rigidly secured to the side wall flanges 6 adjacent the shoulders 8. These hinges 21 are of less width than the shoulders 8 so that when the covers are closed the sides 15 thereof will be substantially flush with the side walls 2 of the box A, and so that the lower edges of the sides 15 will substantially meet the side walls 2 to provide a neat appearing joint. The end walls 17 of the covers B and C, like the side walls 15, when they are closed overlap each other and substantially form continuations of the end walls 3 of the box A.

In order that the trays may be moved into outwardly extending position and in order that they may be moved by the covers B and C, suitable linkages are provided. Thus, links 26 are secured to the outer sides of the flanges 9 of the box and to the opposite ends of the trays D and F near their innermost sides. Links 27 are secured at their lower ends to the flanges 9, at their upper ends to the trays E and G near their innermost sides and intermediate their ends to the ends of the trays D and F near the central portions thereof. Links 28 are also secured to the ends of the trays D and F and to the ends of the trays E and G. The links 26, 27 and 28 are arranged to remain always in parallel relation to each other so that the pivotal connections between the links 26 and 27, and the flanges 9 and trays D and F, and between the links 27 and 28, and the trays D, F, and E, G, respectively, substantially form the corners of parallelograms. The connections of the links to the trays and box flanges may be advantageously made by suitable rivets 29 or any other desirable securing means.

In order that the trays may be operated by the movement of the covers, links 30 are shown as secured to the tray D and cover C and to the tray F and cover B, respectively. The links 30 are preferably secured to the trays D and F at the connections of the links 28 therewith. The outer ends of the links 30, as shown, are offset and secured by the rivets 31 to the end walls 17 of the covers B and C.

The covers B and C may be provided with suitable locking means 32 and the cover B may be provided with a suitable handle 33 so that the carrying case can be conveniently carried.

When the cover B is moved to a partial open position, the trays F and G are moved outwardly, as shown in Fig. 2, and when moved to completely open position the trays 5 F and G are moved to the outwardly extending position shown in Fig. 3. Likewise, when the cover C is moved to open position, the trays D and E are moved to outwardly extending position over the box side wall, as 10 shown in Fig. 3. It will be noted that the height of the side walls 2 of the box portion A is such that the trays 4 and 6 may be readily moved thereover when the trays are moved to outwardly extending position. When in 15 outwardly extending position the trays D and F partially rest upon the horizontal flanges 10 and, if desired, the side walls 2 may be of such height that the trays D and F may rest thereon in extended position. 20 It is also to be noted that the trays E and G are partially supported by the trays D and F respectively, when in outwardly extending position, and that when the trays are in superposed relationship they are supported by 25 the horizontal flanges 10 above the bottom of the box.

The covers when in open position are supported by the links 30 from the trays, these links being preferably of such length that 30 the covers may be maintained in relatively closely adjacent position to the trays.

It is to be particularly noted that when the case is closed, there is relatively little waste space above the uppermost trays. It 35 will moreover be noted that by means of the improved construction a storage space of any desired size may be provided beneath the trays. In such cases the space beneath the trays may also be subdivided into suitable 40 compartments by conventional partition members (not shown).

It will thus be seen by arranging the top and sides of the covers in overlapping relationship, that moisture such as rain cannot 45 readily enter the case to damage the contents thereof.

It will furthermore be seen that an improved case construction is provided wherein 50 a plurality of series of superposed trays may be disposed, such trays being movable into outwardly extended position by a minimum movement of a pair of covers. It will also be seen that the links connecting the trays 55 are secured to the box externally of the offset upper flanges so that such links will be protected at all times.

Furthermore, it is to be understood that the particular features of construction and 60 combinations of parts shown and described, are presented for purposes of explanation and illustration and that various modifications thereof can be made without departing from my invention as defined in the append- 65 ed claims.

What I claim is:

1. In a sheet metal carrying case, a substantially rectangular box having end walls and side walls, said end walls being of substantially the same height as said side walls, offset flanges formed at the upper ends of said end walls, each extending the entire length of said end walls and having a horizontal tray supporting flange thereon at its marginal edge, said horizontal flanges being not lower than the upper edges of said side walls, a plurality of laterally disposed series of superposed trays normally supported on said horizontal flanges, covers hinged to said side walls to cooperatively close said case, 70 said covers having edge portions which continuously overlap at the center of said box and continuously overlap the said offset flanges of said end walls when said covers are in closed position, links secured to said trays and to said offset flanges, whereby said trays may be moved into outwardly extending position upon the opening of said covers and vice versa. 75

2. In a sheet metal carrying case, in combination, a substantially rectangular box having side and end walls of substantially the same height, inwardly offset flanges formed at the upper edges of said walls, said flanges for said end walls having inwardly extending horizontal flanges, a pair of trays normally supported on said horizontal flanges, linkage connecting said trays with said offset end wall flanges, covers hinged to said side walls overlapping each other at the center of said case throughout their entire extent, and linkage connecting each of said trays with one of said covers, whereby the trays and linkage mechanism are protected and whereby said trays may be moved to 80 outwardly extending position and vice versa. 90

3. In a sheet metal carrying case, in combination, a substantially rectangular box having side and end walls of substantially the same height, inwardly offset flanges formed at the upper edges of said walls, said flanges for said end walls having inwardly extending horizontal flanges, a pair of trays normally supported on said horizontal flanges, linkage connecting said trays with said offset end wall flanges, covers hinged to said side walls overlapping each other at the center of said case, and linkage connecting each of said trays with one of said covers, each of said 100 covers having end walls overlapping each other at the center of said case, and the side and end walls of said covers overlying said offset flanges of said side and end walls of said box and being substantially flush with said box walls to provide a rigid and substantially waterproof structure. 110

In testimony whereof I affix my signature.
HARRY P. SHRIVER.
